UNITED STATES PATENT OFFICE.

COLIA V. OLIVER, OF DANVILLE, VIRGINIA.

HOSE-SUPPORTER.

1,235,367.

Specification of Letters Patent. Patented July 31, 1917.

Application filed December 2, 1916. Serial No. 134,661.

To all whom it may concern:

Be it known that I, COLIA V. OLIVER, a citizen of the United States, residing at Danville, in the county of Pittsylvania and State of Virginia, have invented certain new and useful Improvements in Hose-Supporters; and I do hereby declare the following to be a full, clear, and exact description of the invention, such as will enable others skilled in the art to which it appertains to make and use the same.

This invention relates to improvements in hose supporters.

The object of this invention is to improve the construction of hose supporters and provide a hose supporter which will increase the life of a pair of hose due to the fact that it is provided with a pair of clamping members which engage the hose and prevent the tear and wear on the hose at the point of engagement due to the strain necessarily put thereon.

A further object of this invention is to provide a supporter having a peculiar construction of clamping rings whereby the strain usually put upon the point of engagement with the hose is equally distributed entirely around the hose, eliminating likelihood of tearing the same, or in any way injuring the fabric.

A further object of my invention is to provide a hose supporter which will effectively support the hose and prevent the stocking from breaking away at the knees or pulling out.

A still further object of this invention is to provide a hose supporter of this character which will be simple, practical, and comparatively inexpensive in construction, and one that can be manufactured at a comparatively small cost.

With these and other objects in view the invention consists in the novel combination and arrangement of parts hereinafter more fully described and pointed out in the claim hereto appended.

In the drawings:

Figure 1 illustrates a hose supporter constructed in accordance with my invention.

Fig. 2 is a sectional view showing the clamping rings in engagement with the hose, and in operative position,

Fig. 3 is a top plan view of the outer clamping rings,

Fig. 4 is a vertical sectional view of the inner and outer clamping rings, and

Fig. 5 is a fragmentary view of the supporting pad.

Like numerals of reference designate corresponding parts in all the figures of the drawings.

Referring more particularly to the drawings, the numeral 1 designates a body supporting member, in this instance a belt or tape for fastening around the waist of the wearer and having the usual buckle 2 for securing it in position. To the supporting member 1 is attached, by stitching, a suitable body or pad 3, which lies against the abdomen and is of sufficient size to readily accommodate the attachment of a plurality of spaced elastic straps 4 arranged at the lower edge of said pad.

The straps 4 are stitched as at 5 at the lower edge of the pad 3 as is clearly shown in Fig. 1 of the drawings. The lower ends of the straps 4 are provided with the attaching strips 6 which diverge outwardly from the lower ends of the straps 4. These strips 6 are adapted to be secured to the outer clamping rings 7.

The outer clamping rings comprise in their construction two sections and are hingedly connected at one of their edges as at 8 and are provided with a suitable clasp 9 for holding the sections together. The inner faces of the rings 7 are convex, the purpose of which will be hereinafter more fully described.

The straps 6 and a pair of the members 4 are secured to the rings 7 in any suitable manner, as at 11, and are so arranged as to distribute an even pull around the entire ring.

A band ring 12 formed of metal or other suitable material, is substantially concavo-convex in cross section and is adapted to be loosely mounted upon the leg of the wearer, with its concave face outermost. The ring 12 is adapted to have the hose 13 pulled thereover, and the clamping rings 7 secured around the hose and having its convex face 10 binding the hose into the concave face 14 of the ring 12. It will be obvious that the strain placed upon the hose is evenly distributed around the top of the same and not applied to any particular point of engagement of the rings therewith, the

advantages of this in addition to that set forth hereinbefore, being that the stocking is held perfectly smooth all around and any likelihood of the same slipping down eliminated.

The convex face of the inner ring 12 presents a smooth surface which is in contact with the leg of the wearer thereby any fear of the same tearing or scratching the person's flesh is obviated.

In use:

The band 1 is fastened around the waist of the wearer and the ring 12 is slipped upon the legs of the wearer, the stockings are then pulled up over this ring, the clamping rings are then snapped into place around the inner ring and the hose is firmly interposed therebetween and any fear of the tearing or drop stitching of the fabric of the stocking or hose is eliminated, and any fear of the

same slipping down or becoming disengaged is also eliminated.

What is claimed is:

A hose supporter comprising an outer ring having a convex inner face, said outer ring comprising semi-circular sections hingedly connected together, an inner ring having a concave outer face and a convex inner face and adapted to be loosely positioned upon the leg of the wearer, said outer ring having clamping engagement with the concave face of the inner ring, and means connected to the outer ring for supporting the same upon the leg of the wearer.

In testimony whereof I affix my signature in presence of two witnesses.

COLIA V. OLIVER.
